UNITED STATES PATENT OFFICE

154,781

DESIGN FOR A MICROPHONE

Clarence Karstadt, Glen Ellyn, Ill., assignor to
Shure Brothers, Incorporated, Chicago, Ill., a
corporation of Illinois

Application October 13, 1948, Serial No. 149,101

Term of patent 14 years

(Cl. D26—14)

To all whom it may concern:

Be it known that I, Clarence Karstadt, a citizen of the United States, residing at Glen Ellyn, in the county of Du Page and State of Illinois, have invented a new, original, and ornamental Design for Microphone, of which the following is a specification, reference being had to the accompanying drawings, forming a part thereof, in which:

Figure 1 is a front elevational view of a microphone, embodying my new design;

Fig. 2 is a side elevational view of Fig. 1;

Fig. 3 is a rear elevational view of Fig. 1, and

Fig. 4 is a top plan view of Fig. 1.

The dotted lines shown in the several figures of the drawing are for illustrative purposes only.

I claim:

The ornamental design for a microphone, substantially as shown and described.

CLARENCE KARSTADT.
